CLAIM

The ornamental design for an ice fishing knee board, as shown and described.

DESCRIPTION

FIG. 1 is a front perspective view of an ice fishing knee board, showing my new design.

FIG. 2 is a front view of the ice fishing knee board of FIG. 1.

FIG. 3 is a rear view of the ice fishing knee board of FIG. 1.

FIG. 4 is a left side view of the ice fishing knee board of FIG. 1.

FIG. 5 right side view of the ice fishing knee board of FIG. 1.

FIG. 6 is a top view of the ice fishing knee board of FIG. 1.

FIG. 7 is a bottom view of the ice fishing knee board of FIG. 1.

FIG. 8 is a front perspective view of the ice fishing knee board of FIG. 1 in an alternate state of use.

FIG. 9 is a cross-sectional view taken along line 9-9 of FIG. 8; and,

FIG. 10 is a front perspective view of the ice fishing knee board of FIG. 1 with portions removed for clarity of the disclosure.

The broken lines in the drawing views are included for the purpose of illustrating portions of the ice fishing knee board that form no part of the claimed design.

1 Claim, 8 Drawing Sheets
